UNITED STATES PATENT OFFICE

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA

RELEASE MECHANISM

Application filed October 23, 1928. Serial No. 314,511.

This invention relates to improvements in release devices, and the principal object of the invention is to provide a device of this character which shall be simple in form, 5 positive in operation, and unaffected by atmosphere or other variable external conditions.

Another object of the invention is to provide a release device of general application 10 which also shall be particularly well adapted for use in conjunction with thermosensitive control means.

Another object of the invention is to provide a release device adapted for remote control or actuation which by reason of certain 15 inherent characteristics shall be well adapted for use in conjunction with various types of fire extinguishing and control apparatus.

To these general ends, the invention contemplates the provision of a novel trip mechanism which shall be operatively connected by novel means with a suitable thermosensitive or other control or release device or devices which may be located at a remote point 25 or points and which under predetermined conditions shall be effective to release said mechanism.

More specifically, the invention in its preferred embodiment contemplates the provision 30 of a release device for sustained loads responsive to the pressure of the atmosphere whereby an artificially created vacuum is effective to release the said load.

The invention further resides in certain 35 novel and structural details and devices hereinafter set forth including a novel form of junction whereby a single trip mechanism may be connected with a plurality of remote release devices.

In the attached drawings:

Figure 1 is an assembly view of a release mechanism made in accordance with my invention, the trip device forming an element 45 thereof being shown in front elevation;

Fig. 2 is a vertical section on the line 2—2, Fig. 1, showing the mechanism in the "set" position;

Fig. 3 is a front elevation of the trip device with the casing cover removed showing

parts of the mechanism in the relative positions shown in Fig. 2;

Fig. 4 is a sectional view similar to Fig. 2 showing the mechanism in the released condition;

Fig. 5 is a plan view of a preferred form 55 of release device for use in connection with the aforesaid trip mechanism;

Fig. 6 is a section on the line 6—6, Fig. 5;

Fig. 7 is a plan view of a junction box for 60 use in connecting the trip mechanism with a plurality of the release devices shown in Figs. 5 and 6, and

Fig. 8 is a section on the line 8—8, Fig. 7.

With reference to the drawings, the trip 65 mechanism illustrated in Figs. 1 to 4, inclusive, comprises a chamber 1 having a flexible wall 2 in the form of a diaphragm; a member 3 adapted to be retained in a predetermined position against a force tending 70 to move it from said position; a releasable retaining latch 4 for the member 3; and trip mechanism operatively connecting the latch 4 with the diaphragm 2. The entire mechanism, with the exception of the member 3, 75 is in the present instance housed within a casing 5 which includes the chamber 1 and which has in the interior thereof a detachable bracket 6 which in the present instance carries the latch 4 and the trip mechanism. 80

The latch 4 consists of a bell crank lever, one arm 7 of which engages and normally retains the hooked end of the member 3, which latter as clearly shown in the present instance consists of a lever pivoted at 8 between lugs 9 upon the hinged front cover 11 of the casing 5, the lever 3 having projecting therefrom a bail 12 constituting means for attaching an external element to the lever 3. The outer or upper hooked end of the lever 3 85 is adapted to extend inwardly through an aperture 13 in the cover 11 to be engaged by the arm 7 of the latch lever 4, as previously set forth and as illustrated in Fig. 2.

The latch lever 4 in addition to the arm 95 7 comprises a depending arm 14 which is adapted at its lower end to engage behind a shoulder 15 formed on one arm 16 of a lever 17 pivotally mounted at 18 between lugs 19 projecting forwardly from the bracket 6. 100

- The lever 17 also comprises an upwardly extending arm 21 which is adapted to engage behind a shoulder 22 upon a lever 23 pivoted at 24 between lugs 25 projecting forwardly 5 from the bracket 6. The lever 23 extends inwardly and its inner end is adapted to lie beneath a cross piece 26 on a bifurcated lever 27 pivotally mounted at 28 between lugs 29 projecting rearwardly from the bracket 6.
- 10 The lower bifurcated end of this lever 27 straddles a pin 31 connected to the diaphragm 2 and normally engages an enlarged head 32 on said pin. The lever 27 extends upwardly above the pivot 28 and has attached to the upper portion thereof a spring 33, the other end of which in the present instance is attached to a pin 34 on the bracket 6, this spring functioning normally to resiliently retain the lower end of the lever 27 15 against the head 32 of the pin 31.

It will be apparent that the latch 4 is retained in an elevated position adapted to retain the lever 3 in an upright position, as shown in Fig. 2, through the medium of the 20 arm 14 which is held in the advanced position by the shoulder 15 of the lever 17, said lever being held in the advanced position in which the shoulder is effective to hold the arm 14 by the shoulder 22 of the lever 23, 25 which as previously set forth and as shown in Fig. 2 engages the upper end of the arm 21 of the lever 17. The outer end of the lever 23 being normally retained under the cross piece 26 of the lever 27 is prevented from 30 moving upwardly to release the arm 21 until such time as the lever 27 is drawn rearwardly by means hereinafter set forth to an extent such that the member 26 clears the rear end of the said lever 23. The mechanism 35 is shown in Fig. 2 in the "set" condition in which the member 3 is retained in the elevated position.

The diaphragm 2 on one side, that from 40 which the pin 31 projects, is subjected to atmospheric pressure, so that a corresponding pressure in the interior of the chamber 1 permits the diaphragm to assume a normal relaxed position, as in Fig. 2. If this chamber is evacuated, the diaphragm 2 in response to 45 the unbalanced atmospheric pressure on the one side will be flexed, as shown in Fig. 4, this movement of the diaphragm being sufficient to oscillate the lever 27 rearwardly to an extent releasing the lever 23, which 50 thereby is permitted to oscillate upwardly to an extent releasing the arm 21 from the shoulder 22, thereby permitting the lever 17 to oscillate rearwardly, and releasing the arm 14 from the shoulder 15. The arm 14 55 being released, the latch lever 4 is free to oscillate in a clockwise direction, thereby releasing the member 3 which is permitted to fall outwardly on its pivot 8. A spring 60 pressed plunger 30 in the cover 11 acts to 65 force the member 3 outwardly from the

cover. The release positions of the various parts are shown in Fig. 4.

It will be noted that the latch lever 4 has a rearward extension 35 to which is attached a spring 36, the lower end of which is connected to a pin 37 on the bracket 6, this spring functioning, following release of the mechanism as described above, to exert a pressure tending to oscillate the lever 4 counterclockwise into its operative or "set" position. This return oscillation of the lever 4, however, is prevented by a latch 38 pivoted at 39 in the top forward portion of the casing, which under the action of gravity or of a spring 41 moves downwardly from a normal elevated position, as shown in Fig. 2, which it occupies when the parts are set, to the position shown in Fig. 4 in which it engages the arm 7 of the latch lever 4 and prevents a return oscillation of the latter to the operative 85 position. When in the position shown in Fig. 4, it will be noted that the lower end of the arm 14 lies directly above the outer portion of the arm 16 of the lever 17, which prevents this lever from assuming an upright 90 normal position, as shown in Fig. 2. Until, therefore, the latch 38 is moved inwardly and upwardly, the mechanism following a tripping operation cannot be reset.

Resetting of the mechanism is accomplished 95 in part through the medium of the shaft 42 to which the lever 17 is secured and which constitutes the pivot of said lever. This shaft 42 is extended through the casing 5, as shown in Figs. 2 and 3, and has at its outer end a knurled head by means of which the shaft may be manually oscillated. As set forth above, however, the shaft 42 cannot be oscillated to elevate the lever 17 until such time as the latch 38 is shifted inwardly to release the latch lever 4 and to permit the spring 36 to shift this latch lever forward into the normal position. The latch 38 is so arranged in back of the opening 13 as to be engaged by the end of the lever 3 when the latter is moved upwardly into the "set" position whereby in the final movement of this lever into the position shown in Fig. 2, the latch 38 is shifted inwardly, thereby releasing the latch lever 4 and permitting it to oscillate under the action of the spring 36 into the operative or "set" position. This movement of the latch lever 4 permits the operator to oscillate the shaft 42 to bring the lever 17 into the upright position, as shown in Fig. 2.

110 It will be noted that means is provided for retaining the lever 23 in a substantially horizontal position following its release by the lever 27 and the subsequent release of the lever 17. This lever-supporting means in the present instance takes the form of a pin 43 extending between lugs 44 on the bracket 6 underneath the said lever 23. This pin is so arranged that the outer end of the lever 23 115 when supported thereby occupies a position 120

below the part 26 of the lever 27 whereby when air at atmospheric pressure is once more admitted to the chamber 1 and the diaphragm 2 and lever 27 move into the normal position as shown in Fig. 2, this part 26 is adapted to move into a position overlying the outer end of the lever 23. Under these circumstances, the outer end of the lever 23 is again prevented by said part 26 from moving upwardly, and in order to permit the arm 21 to move outwardly to a position behind the shoulder 22, as in Fig. 2, the opening in the outer end of the lever 23 through which the pivot 24 extends is slotted vertically whereby this forward end of the lever may move upwardly sufficiently to permit the upper end of the arm 21 to pass thereunder. In order to immediately return the lever 23 to the normal position and to prevent accidental release of the arm 21 from behind the shoulder 22, I provide a spring 45 which is secured to the bracket 6 and overlies the lugs 25 engaging the top outer portion of the lever 23, as clearly illustrated.

When, therefore, the arm 3 is moved upwardly so that the outer hooked end projects into the opening 13, the latch 38 is forced inwardly, thereby releasing the latch lever 4, which thereupon moves from the position in which it is shown in Fig. 4 to that in Fig. 2, thereby permitting the return of the remaining parts to the "set" position, as shown in Fig. 2, by manipulation of the shaft 42. It will, of course, be understood that prior to these resetting operations, air must be admitted to the chamber 1 to permit the diaphragm to move from the flexed position, as shown in Fig. 5, to the normal relaxed position as shown in Fig. 2.

In conjunction with the foregoing device, I provide suitable means adapted for direct connection with the chamber 1 and actuatable under predetermined conditions to automatically evacuate the chamber 1 which normally is filled with air at atmospheric pressure. A preferred form of this device is illustrated in Figs. 5 and 6 of the drawings. As therein illustrated, the device comprises a casing 46 within which is mounted a sylphon 47. The sylphon is secured in the casing by a cap 48 which is threaded into the upper enlarged part of the casing, which cap member has therein a port 49 and coupling means for connecting with the port a pipe 51. It will be noted that the port 49 communicates with the interior of the sylphon. The cover member 48 also has a port 52 which is controlled by a gravity check valve 53, this valve port also communicating with the interior of the sylphon and permitting the exhaustion of the air or gas contents of the sylphon, while preventing a return flow through the port 52.

In the interior of the sylphon is a spring 54 which tends to expand the sylphon, and the sylphon is also in the present instance

connected through a stem 55 with a thermo-sensitive release device 56 in the lower part of the casing. This latter device comprises in a preferred form a base member 57 threaded into the lower part of the casing 46 and having through said threaded portion an opening 58 through which the stem 55 extends. At the lower end of the passage 58 the member 56 is formed with a seat for a disk 59, this disk having a stem 61 extending outwardly and terminating in a flat disk or head 62. Slidable on the stem 61 is a washer 63, between which and the inner face of the head 62 is confined a body of fusible composition 64, this body being surrounded and confined at the sides by a cap 65 which fits over the head 62 and at its edges engages the washer 63. It will be apparent that so long as the fusible composition remains intact, the washer 63 is prevented from moving towards the head 62. Also slidable on the stem 61 and engaging the outer face of the disk 59 is an arm 66, the extremities of which engage the inner faces of a pair of levers 67, 67, the outer ends of which engage and fulcrum in back of the inwardly beaded annular lower edge 68 of the member 56, while the inner ends thereof engage in back of the sleeve 63. The arrangement is such that in assembly and by reason of the spring 54 within the sylphon 47 a positive pressure is exerted through the stem 55 upon the disk 59 tending to force this disk away from its seat. This, however, is prevented by the arm 66 which bearing against the levers 67 tends to force the outer ends of these levers outwardly about the inner ends as fulcrums, as set forth above. The outer ends of the levers, however, are held inwardly by the washer 63 which is prevented from moving outwardly on the stem 61 by the fusible composition confined between the washer and the head 62, and within the cap 65. When the fusible composition melts under excessive temperature conditions, the washer 63 is freed to move outwardly, thereby releasing the ends of the levers 67 and the arm 66 whereby the disk 59 and stem 61 are free to drop away. This permits the spring 54 to expand the sylphon 47.

In practice, the pipe 51 connected with the interior of the sylphon is also connected with the chamber 1 of the trip mechanism whereby when the sylphon expands, the said chamber 1 is exhausted, with the resultant tripping of the associated mechanism, as set forth above. The release device may be reset after actuation by contracting the sylphon through the medium of the stem 55, which contraction is permitted by the exhaust port 52 through which the air within the sylphon exhausts, the arm 66 and levers 67 being replaced with the stem 61 properly recharged with a fusible composition.

In practice, it is customary in a system including a single trip mechanism to employ

a number of the release devices set forth above, and in order to simplify the connection of these devices with the trip mechanism, as in Fig. 1, I provide the junction box illustrated in Figs. 7 and 8. This junction box comprises a casing 71 having in the bottom thereof a chamber 72 adapted to be connected through a pipe 73 with the chamber 1 of the trip mechanism. The chamber 72 has in the top thereof a pair of ports 74 and 75 each of which is controlled by a gravity check valve 76, which control the connection between these ports 74 and 75 and ports 77 and 78 respectively in the upper part of the casing 71. As shown in Fig. 11, one of these ports, in the present instance the port 77, is connected through the pipe 51 with the sylphon 47 of one of the release devices. If only two of these release devices are used, obviously the sylphon of the second device will be connected through a pipe 79 with the port 78. In the event, however, that more than two of these release devices are employed, the port 78 will be connected with one of the corresponding ports 77 or 78, of a second junction box. The chamber 72 of each of the junction boxes is provided with a second port 81 which if not needed may be plugged up, but which is adapted to receive a pipe running from the corresponding chamber 72 of another junction box. By means of these boxes, any number of the release devices may be connected with a single trip mechanism with a minimum of piping.

35. The herein described device is applicable in principle to any type of release mechanism and is of particular utility in connection with fire control release devices such as fire extinguishers, fire doors and the like.

40. It will be apparent that actuation or release of the sylphon exhauster may be through other mediums or by other means than the thermosensitive one herein disclosed.

I claim:

45. 1. A release device comprising a movable member, mechanism for locking said member in a predetermined position, a chamber having a flexible wall, trip mechanism operatively connecting said flexible wall with the said lock whereby the movement of said flexible wall due to a changing pressure in the chamber releases said lock, a sylphon operatively associated with said chamber, and temperature-controlled means for actuating said sylphon to exhaust the chamber.

50. 2. A release device comprising a movable member, mechanism for locking said member in a predetermined position, a chamber having a flexible wall, trip mechanism operatively connecting said flexible wall with the said lock whereby the movement of said flexible wall due to a changing pressure in the chamber releases said lock, a sylphon operatively associated with said chamber, a spring for actuating said sylphon, means for hold-

ing the spring in a restrained condition, and a temperature-controlled lock for said holding means.

55. 3. A release device comprising a movable member, mechanism for locking said member in a predetermined position, a chamber having a flexible wall, trip mechanism operatively connecting said flexible wall with the said lock whereby the movement of said flexible wall due to a changing pressure in the chamber releases said lock, a sylphon operatively associated with said chamber, a spring for actuating said sylphon, means for holding the spring in a restrained condition, a lock for said holding means, and a fusible link controlling said lock.

60. 4. In a release device for sustained loads, the combination with load-sustaining means, of means including a pressure responsive actuating member for releasing said load, said member being exposed to atmospheric pressure, and evacuating means associated with said actuating member for creating a differential pressure with respect thereto whereby atmospheric pressure is effective to 65 actuate said member to release the load.

65. 5. A release device comprising an actuating member in the form of a flexible diaphragm, said diaphragm constituting a wall of a normally closed system and being exposed to atmospheric pressures, a sylphon operatively associated with said system, thermally-releasable means for normally retaining the sylphon in a contracted condition, a 70 spring for extending the sylphon to evacuate said system and thereby to motivate said diaphragm, and a valve for maintaining said system at a pressure not exceeding atmospheric.

70. 6. A release device comprising an actuating member in the form of a flexible diaphragm, said diaphragm constituting a wall of a normally closed system and being exposed to atmospheric pressures, a sylphon operatively associated with said system, thermally-releasable means for normally retaining the sylphon in a contracted condition, a 75 spring for extending the sylphon to evacuate said system and thereby to motivate said diaphragm, and means automatically operative to prevent the internal pressure of said system from exceeding atmospheric.

75. 7. A release device comprising a normally closed system, an actuating member exposed on one side to atmospheric pressure and at the other side to the internal pressure of said system, the position of said member being controlled by the said opposing pressures, evacuating means associated with said system, means for actuating said evacuator, and means for preventing the internal pressure of said system from exceeding atmospheric.

80. 8. In a release device for sustained loads, the combination with load-sustaining means, of means including a pressure-responsive ac-

tuating member for releasing the load, said member normally being maintained in inoperative position by atmospheric pressure operating at both sides thereof, and means for 5 reducing the pressure at one side of said member whereby the atmospheric pressure at the opposite side is effective to actuate the member to release the load.

9. A release device for sustained loads 10 comprising a fluid-pressure-actuated release element, means whereby said element normally is supported in a predetermined position by atmospheric pressure exerted at opposite sides thereof, and means for reducing 15 the pressure at one side of said element whereby atmospheric pressure at the opposite side effects a movement of the element actuating the release device.

10. A release device for sustained loads 20 comprising a fluid-pressure-actuated release element, means whereby said element normally is supported in a predetermined position by atmospheric pressure exerted at opposite sides thereof, and means for reducing 25 the pressure at one side of said element whereby atmospheric pressure at the opposite side effects a movement of the element actuating the release device.

11. A release device for sustained loads 30 comprising an element operative by predetermined movement from a normal position to release the load, means for utilizing atmospheric pressure to maintain said element in the normal position, and means operative at 35 a predetermined temperature for creating a differential pressure effecting said movement of the element releasing the load.

12. A release device for sustaining loads 40 comprising an element operative by predetermined movement from a normal position to release the load, means for utilizing atmospheric pressure to maintain said element in the normal position, and fluid-pump mechanism 45 for creating a differential pressure effecting said movement of the element releasing the load.

13. A release device for sustained loads 50 comprising an element operative by predetermined movement from a normal position to release the load, means for normally maintaining atmospheric pressures at opposite sides of said element, and means including fluid pump mechanism for creating a differential pressure at opposite sides of said element effecting movement thereof releasing the load.

14. A release device for sustained loads 60 comprising an element operative by predetermined movement from a normal position to release the load, means for normally maintaining equal fluid pressures at opposite sides of said element, and means including fluid pump mechanism for creating a differential 65 in the pressures at opposite sides of said ele-

ment for effecting movement thereof releasing the load.

15. A release device for sustained loads 70 comprising an element operative by predetermined movement from a normal position to release the load, means for normally maintaining equal fluid pressures at opposite sides of said element, fluid pump mechanism for creating a difference in pressure at opposite sides of said element to thereby effect movement of the element releasing the load, and thermosensitive means operative at a predetermined temperature for effecting actuation of said mechanism.

16. A release device for sustained loads 80 comprising an element operative by predetermined movement from a normal position to release the load, said element being normally exposed at the opposite sides thereof to equal pressures, and means for decreasing the pressure at one side of said element to thereby effect movement of the element releasing the load.

17. A release device for sustained loads 90 comprising an element operative by predetermined movement from a normal position to release the load, said element being normally exposed at the opposite sides thereof to equal fluid pressures, and means for evacuating the pressure at one side of said element to thereby effect movement of the element releasing the load.

18. A release mechanism for sustained 100 loads comprising a box, a trip arm mounted on the box for supporting the load, a pendant lever disposed in the box and movable with the trip arm, a diaphragm located in the box, a rockable member pivoted below the pendant lever comprising a long arm, said member also comprising a short arm adapted to be disposed in the path of the pendant lever when the diaphragm is unflexed for holding the trip arm rigid, and means actuated by flexing of the diaphragm to release the pendant lever to permit movement of the trip arm releasing the load.

19. A release mechanism for sustained 115 loads, and an actuator therefor comprising a box, a trip arm mounted on the box to support the load, a pendant lever disposed in the box and movable with the trip arm, a diaphragm located in the box, a rocking member pivoted below the pendant lever comprising a long arm, said member also comprising a short arm adapted to engage the pendant lever when the diaphragm is unflexed for holding the trip arm in the load-supporting position, and means to transmit pressure from the actuator to flex the diaphragm for breaking the engagement of said 120 rocking member with said pendant lever to permit movement of the trip arm releasing the load.

ARTHUR C. ROWLEY.
